UNITED STATES PATENT OFFICE

171,893

COMBINED NAPKIN AND TOOTHPICK HOLDER

Leundy E. Hills, Oakland, Iowa

Application August 10, 1953, Serial No. 26,359

Term of patent 7 years

(Cl. D44—24)

To all whom it may concern:

Be it known that I, Leundy E. Hills, a citizen of the United States, residing at Oakland, in the county of Pottowattamie and State of Iowa, have invented a new, original, and ornamental Design for a combined Napkin and Toothpick Holder, of which the following is a specification, reference being had to the accompanying drawing, forming part thereof.

The figure is a perspective view of a combined napkin and toothpick holder, showing my new design.

I claim:

The ornamental design for a combined napkin and toothpick holder, as shown.
